UNITED STATES PATENT OFFICE.

HOWARD R. HUGHES, OF HOUSTON, TEXAS.

METHOD OF SAPPING OR DESTROYING TRENCHES OR OTHER DEFENSIVE WORKS.

1,278,932.

Specification of Letters Patent. Patented Sept. 17, 1918.

Application filed December 7, 1915. Serial No. 65,472.

To all whom it may concern:

Be it known that I, HOWARD R. HUGHES, a citizen of the United States, residing at Houston, in the county of Harris and State 5 of Texas, have invented certain new and useful Improvements in Methods of Sapping or Destroying Trenches or other Defensive Works, of which the following is a specification.

- 10 This invention relates to a method of sapping or destroying trenches or other defensive works, and is particularly applicable, in military operations, for undermining and destroying the trenches of the enemy.
- 15 It is an old practice in warfare to destroy defensive works by tunneling thereunder, arranging an explosive at the inner end of the tunnel, and then detonating the explosive. Heretofore all the tunneling in these 20 undermining or sapping operations has been accomplished by hand-digging, and all such operations have been accompanied by numerous drawbacks, owing to the limited applicability thereof and to the dangers 25 present. For while tunnels are being driven toward an enemy's defensive works, that enemy is in turn generally actively engaged in driving counter-tunnels and placing counter-mines for the purpose of destroying 30 the tunneling operations and the men engaged in carrying on such operations. It is obvious that any such tunneling operations to be successful must be carried on without the knowledge of the enemy, and the prior 35 methods of carrying on these operations have on that account been very limited in their use, for it is impossible to drive a tunnel by hand through very hard formations, or to properly ventilate a comparatively 40 long tunnel without giving notice to the enemy of the tunneling operations. A very serious defect of the hand-tunneling is that it requires a comparatively long time to dig a tunnel of substantial length. The 45 problem necessary to be solved, therefore, was to provide an adequate means for destroying quickly, and without warning to the enemy, a trench or fortification located at comparatively great distances, as for instance one thousand feet.

I have solved this problem by devising the method hereinafter particularly described. This method consists generally in forming a horizontal or substantially horizontal hole 55 in the ground by means of a rotary boring drill carried by a sectional drill stem whose

length is increased progressively during the drilling operation, the drill stem being operated by means located at the outer end of the hole, and the material that is disintegrated by the drill being carried out of the hole by water under pressure pumped thereinto through the drill stem, forcing an explosive material to the inner end of the hole by means of hydraulic pressure or some 60 similar expedient and exploding the same.

In the method I have devised, the drilling operations are carried on by means, and operators therefor, located in a pit or trench at a safe distance from the enemy's defensive works. The hole bored is of comparatively small size, and the depth to which it can be carried is practically unlimited. Further, by varying the type of drill bit to suit the character of formation being 75 operated upon, this hole can be driven quickly, easily and quietly through any type of earth formation. It is evident, therefore, that in carrying out mining operations by the use of my method, the defects and dangers 80 which have been such a drawback in connection with the hitherto existing methods of carrying on such operations have been practically eliminated.

The object of my invention as set forth 85 above and as more particularly pointed out and described hereinafter is to provide a novel process or method of locating explosives underneath a trench or other object to be destroyed and to provide means for exploding the same. This method is preferably carried out by use of the mechanism hereinafter described and shown in the accompanying drawings; but I do not limit myself to the form of mechanism shown. 95

In the drawings:

Figure 1 is a plan view of said mechanism shown in operative position its relation to the trench to be destroyed being clearly 100 illustrated,

Fig. 2 is a side elevation thereof,

Fig. 3 shows one form of bit employed attached to the drill stem,

Fig. 4 shows another form of bit employed together with a sectional view of the 105 stem and charged cylinder therein,

Fig. 5 shows a longitudinal sectional view of the reamer in collapsed position,

Fig. 6 shows a transverse sectional view thereof taken on the line $a-a$ of Fig. 5, 110

Fig. 7 shows a longitudinal sectional view thereof in operative position,

Fig. 8 shows a sectional view of the trench to be destroyed and the bore underneath,

Fig. 9 shows the enlarged bore and the charged cylinders therein,

5 Figs. 10 and 11 show enlarged views of said cylinders.

Fig. 12 shows the hole terminating at the surface in front of the trench to be destroyed for the purpose of discharging an 10 explosive projectile,

Fig. 13 shows the hole terminating in front of the trench so that the projectile will be exploded by the impact with the wall thereof, and

15 Fig. 14 shows the hole terminating at the surface in front of the trench for discharging, gases and the like in the trench.

Referring now more particularly to the drawings, wherein like numerals of reference designate similar parts in each of the figures, the numeral "1" indicates a section of the trench to be destroyed, which may be protected by wire entanglements "2". Located at a safe distance from this trench

20 25 and within the pit 3 is a drilling machine mounted so as to swing horizontally. By means of this machine radiating holes 4 are drilled which penetrate the ground underneath the wire entanglements and the 30 enemy's trenches and terminate beneath the latter.

The frame 5 of the drilling machine is pivotally mounted upon a suitable base 6, thus permitting it to be swung horizontally.

35 40 45 Mounted in the tubular bearing 7, carried by this frame, is the rotatable sleeve 8 to which the drill stem 9 is clamped, the sleeve and stem being rotated by means of a motor 10 and gear mechanism 11. Rotatably mounted in the frame is a threaded shaft 12 driven by the gear mechanism 13. Attached to the sleeve 8 is a yoke 14 which projects through a slot in the bearing 7 and has an internally threaded bore adapted to coöperate with the 50 55 threads on the shaft 12. Rotation of the shaft 12 thus causes the yoke 14 to move longitudinally thereof and feeds the drill stem as desired. The free end of the drill stem carries a suitable bit 15, the type of which is dependent upon the ground formation present. This bit is connected to the drill stem by a loose-fitting thread.

The drill stem is in the form of a hollow tube or pipe, so that water may be forced 60 therethrough to carry away the materials cut or disintegrated by the drill and also, as will be hereinafter explained, to carry the explosive into position. The drill stem may be lengthened as desired by adding thereto extra sections of the pipe constituting such stem. For the purpose of forcing water through the hollow drill stem, I have provided a pump 17, preferably a three stage centrifugal pump, which is connected to the 65 drill stem by means of a swivel coupling 18.

The water forced through the stem by this pump passes out through the bit at the bottom of the hole and returns on the outside of the stem, carrying the cuttings from the bit with it. In order to prevent excessive 70 erosion at the mouth of the hole, a short length of casing 16 is inserted therein.

The operation of the device is as follows: The drilling machine having been properly mounted in the pit or trench, the drill stem 75 is rotated by means of the motor and coöperating gear mechanisms. At the same time the threaded shaft 12 is rotated by means of the gear mechanism 13 to feed the drill stem forward. The rotary boring tool attached 80 to the drill stem cuts away or disintegrates the material before it, the cuttings being washed out of the hole thus formed by the water supplied under pressure through the drill stem to the end of the hole. As the 85 hole deepens, the drill stem is lengthened by adding extra sections of pipe or tube thereto, and thus a hole of any desired depth can be driven.

It is sometimes desirable to ream out and 90 enlarge the terminus of each hole, underneath the trenches or other object to be destroyed, for the purpose of receiving a plurality of charged cylinders. This may be accomplished by means of a reamer, a preferred form of which is illustrated in Figs. 95 5 and 7.

To so enlarge the hole, the bit 15 is first disconnected from the drill stem. This is accomplished by rotating the drill stem in a 100 reverse direction, which, since the bit 15 is connected to said stem by a loose-fitting thread allowing a ready relative rotation of the drill and stem, causes the stem to unscrew from the head of the bit. The stem 105 is then withdrawn a suitable distance and a reamer, such as illustrated in Figs. 5 and 7, is inserted to ream out and enlarge the hole beyond the free end of the stem. This reamer includes a short pipe section 19 provided with leather cups or washers 20 fitting closely within the stem 9, so that fluid pressure delivered through said stem and acting against said washers will force the reamer inwardly toward the inner free end 110 of said stem. Pivoted within the section 19 are the arms 21, 21, whose outer ends carry the cutters 22, 22 and whose inner ends have the flat springs 23, 23 secured thereto, which springs project through the opposing slots 120 24, 24 cut through said section 19. The outer ends of said arms are in alignment with the deep notches 25, 25 in the corresponding end of the section 19. When it is desired to insert the reamer, the swivel coupling 18 is disconnected and the reamer is inserted within the outer end of the stem 9. The swivel coupling is then again secured in place. Water under pressure is then supplied to the drill stem, driving the reamer 125 130

along to the inner end of the stem. When the cutters 22, 22 pass beyond the inner free end of said stem, they are spread apart, because of the action of the spring 26, which 5 is interposed between the opposite ends of said arms and the outer ends of the arms will move into the corresponding notches 25, 25. At the same time, the springs 23, 23 will seat in the alined grooves 27, 27 in the 10 inner wall of the stem 9, and thus secure the reamer against rotary movement relative to the stem. The springs 23, 23 are connected by means of toggle levers, 28, 28, to which a rod 29 is attached, which rod passes through 15 the plug 36 in the outer end of the section 19. Attached to the outer end of the rod 29 is a wire cable 37, which forces the reamer into the stem. A coil spring 38 surrounds the rod 29 and is interposed between the 20 plug 36, and the inner ends of the toggle levers. This spring normally operates, through said levers, to hold the springs 23, 23 in the grooves 27, 27. When it is desired to withdraw the reamer, the cable is 25 pulled, which operates through the rod 29 and the toggle levers to withdraw the springs 23, 23 from the grooves 24 into the section 19, and into the position shown in Fig. 5, when the reamer may be withdrawn. 30 When the reamer is in operative position, as shown in Fig. 7, rotation of the stem 9 will cause it to ream out and enlarge the inner terminus of the hole as illustrated in Figs. 7, 8, and 9. Orifices 39, 39 are provided through plug 36 to admit a sufficient amount of water to the reamer to carry away the cuttings and thus insure the proper operation thereof.

When the reamer has been withdrawn, the 40 drill stem is advanced to the proper position and the cylinders 30, containing explosive charges, are forced by fluid pressure through the stem and into said enlarged hole. The cylinders have cups or washers 45 31, formed of leather or other suitable material, secured thereto so that the fluid pressure introduced behind them will all be utilized in driving them toward the inner end of the drill stem. The last one of the cylinders introduced has flexible fins 32, secured thereto, which are under compression while the cylinder is within the drill stem and expand after the cylinder has been discharged from the stem and engage with the walls of 50 the hole to secure the cylinder in position. This last cylinder introduced also has an electrical connection 33 attached to an exploding cap carried by said cylinder. The outer end of this electrical connection 33 55 extends through the drill stem and out of the hole so as to be accessible to those operating the drilling mechanism, whereby its charge may be exploded. The explosive charges having been placed in position, the 60 drill stem is then withdrawn, the hole filled 65

with muddy water, the outer end of the hole tamped or plugged and the charge is then ready to be exploded. Exploding the cylinder carrying the electrical connection 33 will operate to explode the other cylinders within 70 the hole, the muddy water and plugged end of the hole preventing back-firing.

It will sometimes be found preferable to employ only one cylinder, as 30', and in such event, when the hole is completed, this 75 cylinder is placed in the stem and is carried by the fluid current, passing through said stem to the inner end thereof. The nose of said cylinder is oval or pointed and seats in the correspondingly shaped counter-bore 34 80 in the bit head, and upon seating in this counter-bore shuts off the flow of water through said head, thereby indicating that the cylinder has reached the inner end of the hole. This cylinder is also provided 85 with cups 31' similar in construction and purpose to the cups 31, and attached thereto is an electrical connection 33', similar to the electrical connection heretofore described, for the purpose of exploding the 90 charge carried in said cylinder. The innermost section of the drill stem is connected to the adjoining section by means of a straight loose-fitting thread. The cylinder 30' is 95 forced into this innermost section by means of fluid pressure, as above explained, and the drill stem is then rotated backward unscrewing at the point 35 and leaving said inner section, the bit and the charged cylinder with the connecting wire 33' at the 100 terminus of the hole underneath the trench or other object to be destroyed. The hole is then filled with mud laden water and the casing 16 is plugged up to prevent back 105 firing in the operating trench.

The cylinders carrying the charge may also contain an explosive and an oil of easy ignition or other inflammable substance or gases that will temporarily disable the enemy, or a substance may be forced 110 through the hole or pipe and discharged into the opposing trench, so as to render the same untenable.

In Fig. 12 I have shown a hole terminating at the surface of the ground in front of the trench 1 so that a projectile as 40 may be forced therethrough by fluid pressure and said projectile is provided with a percussion cap as 41, or with a time fuse (not shown) of the well known construction, so 115 that it will explode upon contact with an object or at a predetermined time.

In Fig. 13 the drill stem is shown withdrawn a certain distance from the end of the hole. In this view the hole terminates 120 near the front wall of the trench and the projectile 40 will be exploded by contact with said wall.

In Fig. 14 I have shown the hole terminating at the surface immediately in front of 125

the trench 1, the pipe therein providing a means for conveying inflammable oil or disabling gases to the enemy's trench.

What I claim is:

- 5 1. The method of undermining military trenches consisting of boring a hole horizontally or substantially horizontal in the ground from an opposing trench, said hole terminating underneath the trench by means operated from said trench to be destroyed, then forcing an explosive to the terminus of said hole by hydraulic pressure.
- 10 2. The method of undermining and destroying defensive works consisting of boring an approximately horizontal hole in the ground to a point in proximity to the works to be destroyed by means of a rotary boring drill operated from the front of said hole, then forcing an explosive to a point adjacent the terminus of said hole by fluid pressure and there exploding the same.
- 15 3. The method of undermining and destroying defensive works consisting of boring a plurality of approximately horizontal holes in the ground by means of a mechanically-operated drilling tool, operating from the entrance to said hole, which holes terminate underneath the works to be destroyed, then forcing a charged cylinder to the inner terminus of each hole by pressure and there exploding the same.
- 20 4. The method of undermining and destroying a military defensive work consisting of boring a plurality of holes which radiate from a common point, said holes terminating underneath the work to be destroyed, then forcing a charged cylinder to the inner terminus of each hole by fluid pressure and there exploding the same.
- 25 40 5. A method of destroying the military defensive work or trench of an enemy which consists in boring a horizontal or substantially horizontal hole in the ground to a point in proximity to the object to be destroyed by means of a mechanically-operated rotary boring tool and a drill stem whose length is increased progressively, and thereafter forcing a destroying agent through the drill stem toward the object to be destroyed.
- 30 45 6. The method of undermining and destroying an object consisting of boring a plurality of holes which radiate from common point and which terminate underneath the object to be destroyed, then forcing an explosive charge to the inner terminus of each hole by fluid pressure and there exploding the same.
- 40 55 7. The method of undermining an object consisting of boring an approximately horizontal hole which terminates underneath said object, then forcing an automatically expanding boring tool by fluid pressure to the inner terminus of said hole and rotating the same to enlarge said bore, then filling

said enlarged portion with explosive charges and there exploding the same.

8. The method of undermining and destroying defensive works, consisting of boring an approximately horizontal hole, which terminates underneath the works to be destroyed by mechanical means located at the entrance to said hole, then forcing a cylinder charged with a destructive agent to the inner terminus of the hole by fluid pressure and causing said agent to act.

9. The method of destroying defensive works consisting of boring an underground hole by means of a mechanically-operated drilling tool, operating from the entrance thereto, and a stream of water that flushes the disintegrated material out of the hole, then forcing an explosive to the terminus of said hole adjacent said works by fluid pressure and there exploding the same.

85 10. The method of undermining and destroying an object consisting of boring an approximately horizontal hole which terminates underneath the object to be destroyed, then forming an automatically expanding reamer to the inner terminus of the hole and rotating the same to enlarge said terminus, then collapsing and withdrawing said reamer and then forcing explosive by fluid pressure into the enlarged portion of said hole and there exploding the same.

100 11. A method of destroying an object located at a distant point, which consists in boring a horizontal or substantially horizontal hole in the ground to a point in proximity to said object by means of a mechanical boring tool that is operated at a point adjacent the front end of said hole, enlarging the inner end of said hole, forcing a destroying agent into the enlarged portion of the hole by a medium under pressure, and thereafter causing said agent to act.

105 110 12. A method of destroying an object located at a distant point, which consists in using a hollow drill stem and a rotary boring tool to form a horizontal or substantially horizontal hole in the ground to a point in proximity to said object, disconnecting said tool from said stem and arranging a reaming tool on the inner end of said stem so as to enlarge said hole, forcing a destroying agent through said stem into the enlarged portion of said hole, and thereafter causing said destroying agent to act.

115 120 125 130 13. A method of destroying the defensive works or trenches of an enemy, which consists in boring a horizontal or substantially horizontal hole in the ground to a point in proximity to the object to be destroyed by means operated from the entrance to said hole and simultaneously arranging a tubular member in said hole, flushing the disintegrated material out of the hole during the drilling operation, and thereafter forcing a

cylinder containing a destroying agent through said tubular member to the inner end of said hole by a medium under pressure and finally causing said destroying agent to act.

14. A method of destroying an object located at a distant point, which consists in 5
boring a horizontal or substantially horizontal hole in the ground to a point in proximity to said object by a mechanical means
10 operated from the front end of said hole, enlarging the inner end of said hole by a

mechanical means, forcing a destroying agent into the inner end of said hole by a medium under pressure, and thereafter 15 using electricity for causing said agent to act.

In testimony whereof I have signed my name to this specification in the presence of two subscribing witnesses.

HOWARD R. HUGHES.
